Inventor,

Howard E. Hearbaugh,
By L. T. Morrison, *Atty.*

UNITED STATES PATENT OFFICE.

HOWARD E. HARBAUGH, OF KENOSHA, WISCONSIN, ASSIGNOR TO THE CHICAGO-ROCKFORD HOSIERY COMPANY, OF SAME PLACE.

MECHANICAL MOVEMENT.

SPECIFICATION forming part of Letters Patent No. 552,527, dated January 7, 1896.

Application filed September 15, 1894. Serial No. 523,165. (No model.)

To all whom it may concern:

Be it known that I, HOWARD E. HARBAUGH, a citizen of the United States, residing at Kenosha, in the county of Kenosha and State 5 of Wisconsin, have invented certain new and useful Improvements in Mechanical Movements, of which the following is a specification.

My invention relates to mechanism for automatically regulating the speed of ratchet-wheels; and it consists of certain new and useful features of construction and combinations of parts specifically devised to that end, all 10 of which are hereinafter fully described, and particularly pointed out in the claims.

Referring to the accompanying drawings, which form a part of this specification, Figure 1 is an isometric view of mechanism embodying my improvement. Fig. 2 is a detailed 15 view of parts of the same.

Like letters of reference indicate corresponding parts in both views.

A is the bed-piece of the machine, provided with an upwardly-projecting annular flange 20 A', preferably integral therewith.

B is a ratchet-wheel mounted on the bed-piece A, concentrically with the annular flange A', provided with a device B', the function whereof will be hereinafter fully 25 described.

C is a standard for supporting parts of the machine, and is fast to the bed-piece A.

E is a rock-shaft mounted in the bed-piece A and bearing E' on the standard C.

F is a walking-beam, mounted on the rock-shaft E, provided with a pallet G, pivot-jointed thereto at F'. The point of the pallet G is rendered longitudinally adjustable by means of the socket G' and set-screw G².

H is a stud rigidly connected with the part F by means of a socket H' and a set-screw H². The stud H obviously might be integral with the part F, but for the convenience of adjusting the same, with reference to the part B', the construction shown is preferable.

I is a rotatable shaft, having a wheel I' fast thereto provided with a cam I² projecting from the inner face thereof.

J is an arm fast by one end to the rock-shaft 50 E and provided at its other end with a roller J' mounted on a bearing J² thereon.

K is a spring normally maintaining the pallet G into engagement with the ratchet-wheel B and the roller J' into engagement with the inner face of the pulley I'. 55

The operation of my machine is as follows: Rotate the wheel I', and the cam I², impinging against the periphery of the roller J', will, through the media of the arm J and rock-shaft E, oscillate the walking-beam F, which 60 will drive the pawl G, thereby rotating the ratchet-wheel B. While the part H is opposite the device B, as shown in the drawings, the pallet G will only pass one tooth of the ratchet-wheel B at each impulse thereof; but 65 after the device B' has traveled out of reach of the part H the oscillations of the walking-beam F will increase in length until the pallet G will pass two teeth of the ratchet-wheel at each impulse. Obviously the device B' 70 may be of any desired width or length within the limits of the mechanism, its width determining the number of teeth that the pallet G will pass at each impulse thereof, and its length determining what part of each revolution of the ratchet-wheel shall be made at its 75 minimum rate of speed, from which it will be seen that the mechanism may be caused to automatically increase or diminish the speed of the ratchet-wheel B at predetermined intervals by employment of the device B', which may be multiplied in number or increased or decreased in width or length, as already stated.

The cam I² on the wheel I' is shown of sufficient width to permit an extreme stroke length by the pallet G of two teeth of the ratchet-wheel B. Obviously if the cam I² were diminished one-half in width the stroke length of the pallet G would be diminished 90 one-half, and if it were doubled in width the stroke length of the pallet would be doubled in length. By width of the cam I² the distance taken transversely through its center parallel to the axis of the wheel I' is meant. 95

The herein-described mechanism, as illustrated in the drawings, is employed as a pattern-wheel for knitting-machines. It obviously might, however, be adapted for use wherever it is requisite to automatically regulate the speed of a ratchet-wheel—that is, cause it to perform a part or parts of a revo-

lution either more or less rapidly than the remainder thereof.

I claim—

1. In a mechanical movement, in combination, a pallet for driving a ratchet-wheel, a ratchet-wheel, a device carried by said ratchet-wheel for regulating the stroke-length of said pallet and a part acted upon by said device and connected to the pallet, substantially as and for the purpose specified.
2. In a mechanical movement, in combination, a walking-beam provided at one end

with a pallet, a rotatably-mounted ratchet-wheel adapted to be engaged and driven by said pallet, a device carried by said ratchet-wheel—acting through the free end of the walking-beam—for regulating the length of the stroke of the pallet, and means for oscillating said walking-beam, substantially as and for the purpose specified. 15

HOWARD E. HARBAUGII.
